CLAIM

The ornamental design for a paper towel dispenser adapter, as shown and described.

DESCRIPTION

FIG. 1 is a perspective view showing a first embodiment of a paper towel dispenser adapter in accordance with our new design;

FIG. 2 is a top plan view thereof, the bottom plan view being identical thereto;

FIG. 3 is a side elevation view thereof, the other side elevation view being identical thereto;

FIG. 4 is a front elevation view thereof, the rear elevation view being identical thereto;

FIG. 5 is a perspective view showing a second embodiment of a paper towel dispenser adapter in accordance with our new design;

FIG. 6 is a top plan view thereof, the bottom plan view being identical thereto;

FIG. 7 is a side elevation view thereof, the other side elevation view being identical thereto;

FIG. 8 is a front elevation view thereof, the rear elevation view being identical thereto;

FIG. 9 is a perspective view showing a third embodiment of a paper towel dispenser adapter in accordance with our new design;

FIG. 10 is a top plan view thereof, the bottom plan view being identical thereto;

FIG. 11 is a side elevation view thereof, the other side elevation view being identical thereto;

FIG. 12 is a front elevation view thereof, the rear elevation view being identical thereto;

FIG. 13 is a perspective view showing a fourth embodiment of a paper towel dispenser adapter in accordance with our new design;

FIG. 14 is a top plan view thereof, the bottom plan view being identical thereto;

FIG. 15 is a side elevation view thereof, the other side elevation view being identical thereto; and,

FIG. 16 is a front elevation view thereof, the rear elevation view being identical thereto.
